UNITED STATES PATENT OFFICE.

THOMAS J. COO, OF TORONTO, ONTARIO, CANADA, ASSIGNOR TO THE MONARCH TYPE-WRITER COMPANY, OF SYRACUSE, NEW YORK, A CORPORATION OF NEW YORK.

TYPE-WRITING MACHINE.

974,237.

Specification of Letters Patent.

Patented Nov. 1, 1910

Application filed October 21, 1907. Serial No. 398,424.

To all whom it may concern:

Be it known that I, THOMAS J. COO, a subject of the King of England, and resident of Toronto, Province of Ontario, in the county of York and Dominion of Canada, have invented certain new and useful Improvements in Type-Writing Machines, of which the following is a specification.

My invention relates to typewriting machines and more particularly to means for controlling the work sheets at and adjacent to the printing point.

The devices of my invention are particularly efficient for use in writing cards and are in the nature of a card holder which compels the card to hug the platen snugly at all points at and adjacent to the printing point, both above and below the printing line and at either side of the printing point, thus avoiding blurring imprints.

The objects of my invention are to provide simple, efficient and inexpensive means of the character specified which offer no appreciable obstruction to the operator's view of the writing and which are in the nature of an attachment that may be applied to existing forms of typewriting machines.

To the above and other ends which will hereinafter appear, my invention consists of the features of construction, arrangements of parts and combinations of devices to be hereinafter set forth and particularly pointed out in the appended claims.

In the accompanying drawings wherein like reference characters indicate corresponding parts in the different views, Figure 1 is a fragmentary front elevation showing a sufficient number of parts of a typewriting machine to illustrate my invention in its embodiment therein. Fig. 2 is a vertical fore and aft sectional view of the same.

My invention is in the nature of an improvement on the construction shown in the patent to George A. Seib No. 821,382, dated May 22nd, 1906, and I have illustrated the invention embodied in the Monarch machine, though it should be understood that the invention may be employed in other styles of typewriting machines.

The platen 1 is journaled in end plates 2 which project forwardly from a cross bar 3 mounted to travel on ball bearings between fixed rails 4 secured to brackets 5 which project upwardly from the top plate

6 of the machine. Arms 7 project forwardly from lugs 8 on the cross bar 3, the arms 7 being secured to the lugs by screws 9. The supporting arms 7 are connected at their forward ends to and support a combined carriage and platen scale 10 which coöperates with the platen below the printing line indicated by the dotted line *a* in Fig. 1. Segmentally arranged type bars 11 are pivoted at 12 and strike upwardly and rearwardly against the front face of the platen 65 and are actuated through the links 13 by suitable key actuated means such as those employed in the Monarch machine, for instance.

A front plate 14 is secured by screws 15 to lugs 16 which project downwardly from the top plate 6 at the forward edge thereof. A bracket 17 is secured to the front plate by shouldered screws 18 which extend through slots 19 in a vertically movable plate 20. The upper portion of the bracket 17 is provided on the sides thereof with ears 21 to which a card guide or holder, designated as a whole by the reference numeral 22, is pivoted at 22. The main body portion of this card guide is substantially H-shaped and depending arms 23 thereof are bent forwardly as shown in Fig. 2 to form cam surfaces with which forwardly projecting fingers 24 on the sliding plate 20 coöperate. Finger pieces 25 project forwardly from the sliding plate in order to facilitate a vertical adjustment thereof. A coiled spring 26 surrounds the pivot 22 and normally presses the upper end of the card guide or the holder toward the platen, the holder being pressed or held more rigidly against the platen when the sliding plate 20 is in the upper position. The arms 27 of the upwardly projecting portion of the card guide or holder are disposed on opposite sides of the printing point which is indicated at *a* in Fig. 1; and the upper edges of these arms are made straight at 28 to form line indicators, the space between the arms 27 constituting a printing point indicator. A pointer 29 is formed on the card guide or holder for coöperation with the lower set of indices 30 on the combined platen and carriage scale. The construction thus far described is similar to that disclosed in the patent to Seib hereinbefore referred to.

The arms 27 are perforated at 31 to receive the bent ends 32 of a wire extension which is in the general form of an inverted W, the ends 32 of this guide being soldered or otherwise secured in place. The arms 33 extend upwardly and inwardly from the ends 32 thereof and are connected at their upper ends by loops or curves 34 with downwardly and inwardly extending branches or 10 arms 35 which terminate in a central loop 36, the loop 36 and the lower parts of the arms 35 being received between the arms 27 of the card guide 22. From an inspection of the drawing it will be seen that the arms 15 33 extend toward the platen from the ends 32 thereof and each arm has a sharp bend 37 where it is brought into contact with the platen or the work sheet thereon and from this point, the upper parts of the arms or 20 sections 33 and 35 conform to the curvature of the platen. The loop 36 is bent slightly forwardly away from the platen and extends in front of and adjacent to the platen scale 10. It will be seen that a set of arms 25 33, 35 is situated at each side of the printing point and that the arms of each set are spaced apart. The wire extension is secured to the card guide only at the ends 32 and there is a certain degree of inherent 30 resiliency in the wire extension and in its connection with the card guide 22. It will be observed that the wire extension extends above and below and crosses the printing line and that the arms 35 coöperate with the 35 card or work sheet on opposite sides of the printing point α and adjacent thereto and that the arms 33 also coöperate with the card or work sheet on each side of the printing point but at a distance more remote 40 from the printing point than the arms 35 and that the work sheet or card will be maintained snug against the platen by the card guide or holder from the time any given point on the card leaves the platen 45 scale until it passes to a considerable distance above the printing line. It will also be seen that notwithstanding the fact that the wire extension of the card guide extends across the printing line it offers no 50 appreciable obstruction to the operator's view of the writing, the arms 33 and 35 being spaced apart and of small cross-section; nor does the extension interfere with the operator's view of the line indicating 55 edges 28; nor does the extension interfere with the operator's view of a printed line of writing when it is brought into coöperation with the line indicating edges 28 of the guide. This is a matter of importance 60 in visible writing machines for which the invention is more particularly adapted. It will be understood that according to my present invention all of the advantages of the card guide and holder of the Seib patent 65 are attained and that the wire extension at-

tains the additional advantage of assuring a maintenance of the work sheet or card snugly against the face of the platen above the printing line as well as below it and to a considerable distance on both sides of the 70 printing point to prevent blurring imprints from being produced.

It will be seen that the devices of my invention are carried by a fixed portion of the machine and remain fixed during the travel 75 of the carriage, and when I refer in the accompanying claims to a fixed card guide or device I mean that it shall be fixed in the sense above described as distinguished from the part which is carried by and travels 80 with the platen or carriage:

What I claim as new and desire to secure by Letters Patent, is:—

1. In a typewriting machine, the combination of a platen, and a card guide carried 85 by a fixed portion of the machine and having a wire extension that crosses the printing line and is looped at the top and bottom.

2. In a typewriting machine, the combination of a platen, and a card guide having 90 openings in the guiding portions thereof through which the writing may be seen, said guide being carried by a fixed portion of the machine and having an extension that crosses the printing line and is in the general form of an inverted W. 95

3. In a typewriting machine, the combination of a platen, and a card guide carried by a fixed portion of the machine and having two sets of arms with openings between 100 the arms of each set, said arms extending across the printing line with one set on each side of the printing point.

4. In a typewriting machine, the combination of a cylindrical platen, and a card guide 105 carried by a fixed portion of the machine and having two sets of arms with openings between the arms of each set, said arms forming generally to the curvature of the platen and extending across the printing 110 line with one set on each side of the printing point.

5. In a typewriting machine, the combination of a platen, a card guide carried by a fixed portion of the machine and having two 115 sets of arms with openings between the arms of each set, said arms extending across the printing line with one set on each side of the printing point, and spring means for effecting a pressure of said arms against the 120 platen.

6. In a typewriting machine, the combination of a platen, and a card guide carried by a fixed portion of the machine adjacent to the printing point, said guide having line 125 indicating edges, printing point indicating means and an extension comprising a plurality of sets of arms which extend across the printing line on opposite sides of and adjacent to the printing point, a set of such 130

arms being on each side of the printing point, and the arms of each set being spaced apart.

7. In a typewriting machine, the combination of a cylindrical platen, and a card guide pivoted to a fixed portion of the machine adjacent to the printing point and spring pressed toward the platen, said guide having line indicating edges, printing point indicating means, and a wire extension comprising a plurality of sets of arms which extend across the printing line on opposite sides of and adjacent to the printing point

and conforming generally to the curvature of the platen, a set of such arms being on each side of the printing point, and the arms of each set being spaced apart.

Signed at the borough of Manhattan, city of New York, in the county of New York, and State of New York this 19th day of 20 October A. D. 1907.

THOMAS J. COO.
